UNITED STATES PATENT OFFICE

91,782

DESIGN FOR A SCALE

James Douglas Lorenz, Dayton, Ohio, assignor to
International Business Machines Corporation,
New York, N. Y., a corporation of New York

Application February 9, 1934, Serial No. 50,678

Term of patent 14 years

To all whom it may concern:

Be it known that I, JAMES DOUGLAS LORENZ, a citizen of the United States, residing at Dayton, in the county of Montgomery and State of Ohio, have invented a new, original, and ornamental Design for Scales, of which the following is a specification, reference being had to the accompanying drawings, forming a part thereof.

Fig. 1 is a perspective of the scale viewed from the merchant's side, showing my new design.

Fig. 2 is an elevation thereof from the customer's side.

Fig. 3 is a plan view thereof, and
Fig. 4 is an end perspective view thereof.

I claim:

The ornamental design for a scale as shown.
In testimony whereof I hereto affix my signature.

JAMES DOUGLAS LORENZ.
